(57) **CLAIM**

The ornamental design for a venous blood collection device, as shown and described.

DESCRIPTION

FIG. 1 is a perspective view of a venous blood collection device, showing our new design;

FIG. 2 is a side elevation view showing the wider side thereof; FIG. 3 is a side elevation view showing the thinner side thereof;

FIG. 4 is a top plan view thereof; and,

FIG. 5 is a bottom plan view thereof.

The broken lines are included in the drawings for the purpose of illustrating unclaimed portions of the venous blood collection device and form no part of the claimed design.
